DRIVING TOOL FOR EYE-SCREWS

Joseph H. Alliano, Santa Ana, Calif.

Application January 22, 1952, Serial No. 267,569

2 Claims. (CL. 145—50)

1

This invention relates to a hand-tool for driving eye-screws, either with or without attached prongs, and has as a particular object the provision of a simple and handy tool which substantially reduces the time, bother, and uncertainty ordinarily required and suffered in driving such screws. My invention works with equal facility to drive screw-hooks or any other type of screw having a thin head in extension of the threaded portion of the screw, and its advantages for such operations as driving cup-hooks in the underside of a pantry shelf will be hereinafter obvious.

A further object of my invention is to provide a tool for the above-stated purposes which may in its simplest form be fitted to a screw-driver, either of the simple rigid type or of the ratchet or quick-acting type, so that it may be used advantageously by professional carpenters as well as by housewives and less skilled persons.

Still another object of my invention is to provide a tool for driving eye-screws with attached hooks which receives and guards the hooks so that an unwary person is not injured thereby.

Another object is to provide a tool which holds an eye-screw firmly in prolongation of the axis of the tool, so that the eye-screw may be started by tapping or applying pressure to the tool.

In its broad characteristics, my invention comprises an elongated body having in one end a pair of transverse grooves, at a right angle one to another and forming a recessed cross at the center of the body end. One of the grooves is shallower than the other and has a V bottom, the V being deeper and more acute towards the center of the body so as to grip firmly the extension of a screw such as an eye or a cup-hook. The other groove may be broader and rounder, to form a recess for receiving the eye of a hook engaged with the eye of a screw. The end of the body opposite to said grooves may have a slot to receive the end of a screw-driver, or the body itself may serve as a handle to provide twisting leverage. If the body is enlarged for the last named purpose, the second mentioned deeper groove may be extended along one side of the body to receive the hook-portion of a driven article.

In the accompanying drawings, illustrative of preferred and modified embodiments of my invention,

Fig. 1 is a side elevational view of a form of my invention suitable for use as an extension on a screw-driver;

Fig. 2 is an elevational view of the same tool at a change of orientation of ninety degrees;

Fig. 3 is a top end view, in the orientation of Fig. 1;

2

Fig. 4 is a bottom end view, in the orientation of Fig. 2;

Fig. 5 is a longitudinal sectional view on the line of section 5—5 of Fig. 3;

Fig. 6 is a longitudinal sectional view on the line of section 6—6 of Fig. 3;

Fig. 7 is an elevational view of a modified form of my invention in which the body of the tool forms an operating handle;

Fig. 8 is an end view taken from the right of Fig. 7;

Fig. 9 is an end view taken from the left of Fig. 7; and

Fig. 10 is a perspective view illustrating a method of operation.

Having reference now to the details of the drawing, I have shown in Figs. 1 to 6 a driving tool having an elongated body 11 and having its base end 12 cleft by a slot 13 suitable for receiving as 10 the blade of a screw-driver. The bifurcated portions of the base end 12 forming the slot 13 preferably have small flanges 14, shown in Fig. 4, to prevent a screw-driver blade from slipping out of the slot. The opposite end 15 of the body 11 is preferably flattened to be substantially oblong in cross-section as shown in the end view of Fig. 3, and is doubly forked. A deep groove 16 traverses the end 15 in its lesser dimension to form one fork. The groove 16 is of sufficient width to hold as 20 a body attached to an eye-screw such as the eye of a hook, without binding thereon, and as it is not intended to bind it may have a rounded or flat bottom 17. Centrally traversing the end 15 in its longer dimension to form a second fork and as 30 crossing the groove 16, is a shallower groove 18, which may be somewhat narrower than the groove 16 so as to hold the eye of a screw slidably but without material play. The grooves 16 and 18 jointly form a deeply recessed cross in the end as 35 15. The bottom of the groove 18 is sloped so as to be deepest at its intersection with the groove 16 and is formed with V-notches 19 which are widest at the exterior ends of the groove and narrowest at the points where the groove 18 is as 40 intersected by the deeper groove 16.

To drive an eye-screw with this tool, the eye of the screw is placed in the shallow groove 18 and pressed firmly so that the V-notches 19 may grip the rim of the eye. If a hook, also having an eye, is interlocked with the eye-screw, the eye of the hook is placed in the deeper groove 16, permitting the hook to extend laterally from the body 11. With the blade of a screw-driver inserted in the slot 13, the screw-driver may be tapped or pressed to start the eye-screw and may then be rotated to drive the screw. Because the

V-notches 19 engage spaced points on the rim of the eye of the screw and the threaded body of the screw is in axial prolongation of the body 11, both torque and end-pressure are evenly applied and there is little tendency for the screw to tilt while it is being started. Instead of having to guide and support the screw with one hand while applying torque with the other, the operator handles only the screw-driver and may have one hand free. Obviously the groove 16 may hold the hook of a cup-hook as well as it holds the eye of a latch hook.

In the modified form of my invention shown in Figs. 7 to 10, the body 21 has the general form and dimensions of an ordinary screw driver handle, so that it may be used without an auxiliary tool if desired, although its base end 22 may also be provided with a slot 23 for receiving an auxiliary tool such as a screw-driver. Starting near the end 22 and extending to the opposite end 25, is a groove 24, which becomes progressively deeper as it approaches the end 25 until it connects with the bottom 27 of a deep diametrical transverse groove 26 at the end 25, corresponding in function to the groove 16 heretofore described. Preferably the body 21 has sufficient thickness at the end 25 to permit the groove 26 to receive the eye of an attachment to the eye-screw—such as the eye of a latch-hook—without emerging through the wall of the body 21 opposite to the groove 24, thus affording wall strength to the forked end 25. A shallow diametrical groove 28 in the end 25 crosses the groove 26 at a right angle, and is bottomed in V-notches 29, the groove 28 and notches 29 corresponding in form and function to the hitherto described groove 18 and notches 19, and likewise forming a deeply recessed cross in the end 25. Near the end of the groove 24 nearest the base end 22 is a hole 30 extending radially inwardly from the bottom of the groove.

In view of the described operation of the preferred form of my invention, the operation of this modified form will be obvious. The groove 24 and hole 30 permit the shank 31 of a hook 32 to be placed in the groove 24 in parallel relationship to the body 21, rather than radially, and to be held there conveniently by placing the point 33 of the hook in the hole 30. Thus the hook is never in the way, and the operator's hands are protected from possible injury by the hook. The eye 34 of an eye-screw 35 will be firmly engaged in the notches 29 of the groove 28, to hold the screw in axial prolongation of the body 21. The

5 eye 34 interlocks with the eye 36 of the hook 32 at the intersection of the bottom of the groove 28 with the groove 26, but the hook is so held by the grooves 26 and 24 that it exerts no disturbing torque upon the eye-screw.

10 As further modified body forms of my invention may be developed without departure from the spirit of my invention, I do not wish to be limited to the precise examples herein described, but desire the scope of my invention to be interpreted as commensurate with the appended claims.

I claim:

15 1. In a tool for driving eye-screws and like articles, a body having a groove bifurcating a portion of said body and having a second and deeper groove intersecting said first-mentioned groove; the walls of said first-mentioned groove being convergent adjacent the bottom of said groove to grip an article disposed in said groove at positions on opposite sides of said second groove, the bottoms of said first-mentioned groove at said positions being substantially normal to radii of a circle having its center within said first-mentioned groove in the plane of said intersecting groove.

20 2. In a tool for driving eye-screws and like articles, a body having a groove bifurcating a portion of said body for receiving the eye portion of a screw, and having a second groove intersecting said first-mentioned groove at substantially a right angle so as to form a deeply recessed cross, said second groove being deeper than said first-mentioned groove to receive an attachment to said eye portion and extending away from said recessed cross along a side of said body to receive a shank of said attachment.

JOSEPH H. ALLIANO.
